UNITED STATES PATENT OFFICE.

JAMES E. ALLISON, OF ST. LOUIS, MISSOURI, ASSIGNOR TO HIMSELF AND
GEORGE M. SEELEY, OF ST. LOUIS, MISSOURI.

BLOCK-SIGNALING SYSTEM AND APPARATUS THEREFOR.

SPECIFICATION forming part of Letters Patent No. 744,706, dated November 24, 1903.

Application filed August 30, 1902. Serial No. 121,652. (No model.)

To all whom it may concern:

Be it known that I, JAMES E. ALLISON, a citizen of the United States, residing at the city of St. Louis, State of Missouri, have invented 5
a certain new and useful Improvement in Block - Signaling Systems and Apparatus Therefor, of which the following is a full, clear, and exact description, such as will enable others skilled in the art to which it appertains 10 to make and use the same, reference being had to the accompanying drawings, forming part of this specification, in which—

Figure 1 is a fragmentary view showing the signals at one point in the line. Fig. 2 is a 15 top plan view of the same, partly in section. Fig. 3 is an elevation showing the signals at the ends of four blocks, and Fig. 4 is a dia-grammatic view.

My invention relates to improvements in 20 block-signaling systems and apparatus for use in the same.

My object is to provide a system in which the signals are operated automatically, the system being adaptable to a single-track road 25 and the train or car serving to automatically open and close the blocks.

To these ends and also to improve generally upon systems and apparatus of the character indicated my invention consists in the 30 various matters hereinafter described and claimed.

In the accompanying drawings, 1 represents a track, and 2 a line-wire or trolley-wire along the same. At suitable intervals along the track standards 3 are erected, by means of 35 which the track is divided into blocks, four of these blocks being here indicated and being marked A, A', A², and A³, respectively. It will of course be understood that the line 40 need not be divided into blocks throughout its entire length; but the blocks can be provided only about curves and other places at which an approaching train or car cannot be seen for a long distance.

Upon each standard are mounted two signals M and N, these signals being here shown 45 as cylindrical blocks 5, having cylindrical lanterns 6 mounted thereon. One face or quadrant of each block is painted white, and 50 the adjacent face or quadrant of said block is painted red, while each lantern is provided

with two windows, which are above the painted faces of the supporting-block and are colored to correspond with the said faces. The signals being cylindrical, practically no surface 55 is presented to the wind to retard the operation of the signal. Each block is mounted upon a spindle or shaft 7, suitably journaled in a supporting-casing 8 upon the standard, and fixed upon the spindle is a drum or pul- 60 ley 9. Suitably mounted in the casing are solenoid-magnets 10, whose cores 11 are connected to opposite ends of a chain or other suitable driving member 12, passing about the drum and engaging the same in such manner that the spindle is partially rotated as a core is retracted. A locking-lever 13 is provided at one end with a locking finger or detent 14, which is adapted to be received in either of the notches or recesses 15, provided 65 upon the drum 9, and the opposite end of said locking-lever is connected to the core 16 of a solenoid-magnet 17, a spring 18 serving to move the lever into locking position.

Switches 19 and 19^a are located along the 70 track, a pair of such switches being placed at substantially the point at which each standard 3 is erected, the switches 19 being adapted to be operated by a train bound in one direction and the switches 19^a being adapted to 75 be operated by a train bound in the opposite direction. Each switch comprises a pivoted arm or lever 20 and four contact places with which said arm is adapted to simultaneously engage when it is thrown by a passing 80 train or car, said arm being normally held out of contact with said plates and being returned to such position, as by means of a spring 21. The contact-plates of the switches 19 are marked 22, 23, 24, and 25, respectively, 85 and the contact-plates of the switches 19^a are respectively marked 22^a, 23^a, 24^a, and 25^a. The solenoid-magnets 10 are arranged in pairs, the magnets of a given pair operating upon a single spindle, and those magnets 90 which when energized cause a spindle to be thrown to display the red light and face are marked R, while the magnets which when energized cause the white light and face to be displayed are marked W. Each contact-plate 25 is connected by a wire *a* to the solenoid W of the signal M, located at the point 95 100

at which the switch, including said plate, is located. Each contact-plate 24 is connected by a wire *b* to the solenoid *R* of the signal *N*, which is supported upon the standard which 5 carries the last-mentioned signal *M*. Each contact-plate 22^a is connected by wire *c* to the solenoid *R*, operating the signal *M* at the point at which the particular plate 22^a is located, and each contact-plate 23^a is connected 10 by wire *d* to the solenoid *W*, operating the signal *N* at the said point. Each contact-plate 23 is connected by the wire *e* with the wire *c* of the next signal mechanism upon one side of the block end at which the particular 15 plate 23 is located, and each plate 22 is connected by the wire *f* with the wire *d* of the signal mechanism located upon the opposite side of the said block end. Each contact-plate 24^a is connected by the wire *g* with the 20 wire *b* of the signal mechanism upon one side of the block end at which the particular plate 24^a is located, and each contact-plate 25^a is connected by the wire *h* with the wire *a* of the signal mechanism upon the opposite 25 side of the said block end—that is to say, when the switch-arm 20 is thrown it operates four signals, two of these being located at the block end at which the switch-arm is located, the third being located at the block 30 end next adjacent that at which the switch is located and upon one side of the same, and the fourth signal being located at the block end next adjacent that at which the switch is located and upon the other side of the 35 same. Each locking-lever-controlling solenoid 17 is connected by a wire *i* to the ground and by a wire *k* to one of the magnets *R* or *W* of a pair, the other magnet of the pair being connected to the said wire *k* by a branch 40 wire *l*. Each switch-arm 20 is connected to the line-wire 2 by means of a wire *o*. It will therefore be seen that when a switch-arm is thrown connection is established between the line-wire and the ground and one solenoid 45 of an appropriate pair of magnets *R* and *W* is energized, the solenoid 17, controlling the locking-lever acting upon the spindle operated by said pair of solenoids *R* and *W*, being also energized whenever one of said 50 magnets of said pair is energized. Thus simultaneously with the energizing of either magnet of a pair the locking-lever-controlling solenoid, which cooperates with said pair, is energized and the locking-lever is carried out 55 of locking position, thereby permitting the proper solenoid *R* or *W* to operate and to throw the signal. As soon, however, as the solenoid *R* or *W* is deenergized the solenoid 17 is also deenergized and the locking-lever 60 is thrown by its spring 18 into position to lock the signal in the position into which it has just been brought.

The various signals are arranged in line with each other along the track, so that there 65 is a separate signal controlling each end of a block when viewed from either direction along the track. For example, the signal *M*, sup-

ported upon the right-hand standard shown in Fig. 3 of the drawings, controls one end of the block *A'*, and the signal *N*, mounted upon 70 the middle standard shown in Fig. 3, controls the other end of said block *A'*, while the signal *N* of the right-hand standard shown in 75 said figure controls one end of the block *A*, and the signal *M* upon the middle standard controls one end of the block *A²*. Therefore 80 the signals can be used to properly signal a train approaching a block end from either direction. When a train or car is traveling in a given block—as shown, for example, in the 85 block *A²*—the signals controlling the ends of the said block are turned to display the red lights and faces.

We will assume that a car is traveling in the direction of the arrow shown in Fig. 3 and 90 is in the block *A'*. In such event the signal *M* upon the right-hand standard 3 will display the red light and face to close the rear of the said block *A'*, and the signal *N* upon the center standard 3 will show the red light 95 and face to close the forward end of the said block, while the signal *N* upon the right-hand standard 3 will display the white light and face, and the signal *M* on the middle standard will also display the white light and face. 100 As long, therefore, as the car remains in the said block *A'* no other car can enter this block from either direction. As the car leaves the block *A'* and passes into the block *A²*, it operates the switch 19^a. As the arm 20 of the 105 switch is thrown and makes connection with the plates 22^a, 23^a, 24^a, and 25^a, the magnet *R* of the signal mechanism at the point which the car is passing will be energized, and the signal *M*, at the rear of the block *A²*, upon 110 which the car is entering, will be thrown to display the red light in order to close the rear of the block into which the car is passing. The solenoid *W* of the signal *N*, located at the same point, will also be operated in order 115 to cause the said signal *N* to display the white light, thereby opening the block *A'*, which the car is just leaving. The magnet *W* of the signal mechanism at the rear of the block which the car is leaving will be operated to 120 cause the signal *M* to display its white face and light, thereby opening the other end of the block which the car is leaving, and the magnet *R* of the signal *N* at the forward end 125 of the block *A²*, into which the car is passing, will be operated in order to close the forward end of the block upon which the car is about to travel. As the car leaves the block *A²* and enters block *A³*, the signals for said blocks will be operated in the manner just described in connection with the signals for the blocks *A'* and *A²*. Of course, if a car is, for example, in the block *A²*, as shown in Fig. 3, and is traveling in the direction of the arrow 130 the signal *M* immediately in advance of the car controls the movement of said car beyond said block, and if while the car is in the block *A²* a car should enter the block *A³*, traveling in the direction opposite to the arrow

shown, the signal M upon the left-hand standard would immediately be thrown to display the red light and face to the car in the block A², and the travel of said car would therefore be stopped.

I am aware that minor changes in the arrangement, construction, and combination of the several parts of my system and apparatus can be made and substituted for those here-
10 in shown and described without in the least departing from the nature and principle of my invention.

Having thus described my invention, what I claim, and desire to secure by Letters Patent, is—

1. In a system of the character indicated, the combination with a track divided into blocks, of two signals at the meeting-point of each two blocks, one of said signals being a 20 forwardly-exhibiting one, N, and the other of said signals being a rearwardly-exhibiting one, M, two operative mechanisms for each of said signals, one mechanism of each said set of operative mechanisms being a "danger" mechanism, R, and the other thereof being a "safety" mechanism, W, a single movable element,^{19a}, at the meeting-point of each two blocks and adapted to be operated as a car passes forwardly from one block to the 30 next, a second movable element, 19, at the meeting-point of each two blocks and adapted to be operated as a car passes rearwardly from one block to the next, four members at each of said meeting-points, the said four 35 members at a given meeting-point coöperating with the said single movable element at said meeting-point which is operable as a car passes forwardly, and being operatively connected as follows: one with the "safety" 40 mechanism of the rearwardly-exhibiting signal at the next rear meeting-point, one with the "danger" mechanism of the forwardly-exhibiting signal of the next forward meeting-point, one with the "safety" mechanism 45 of the forwardly-exhibiting signal at said

given meeting-point, and one with the "danger" mechanism of the rearwardly-exhibiting signal at said given meeting-point, and four members at each of said meeting-points, the said last-mentioned four members at a given 50 meeting-point coöperating with the said single movable element at said meeting-point which is operable as a car passes rearwardly, and being connected as follows: one with the "safety" mechanism of the rearwardly-ex- 55 hibiting signal at such given meeting-point, one with the "danger" mechanism of the forwardly-exhibiting signal at said given meeting-point, one with the "danger" mechanism of the rearwardly-exhibiting signal at the next rear meeting-point, and one with the "safety" mechanism of the forwardly-exhibiting signal at the next forward meeting-point; substantially as described.

2. In apparatus of the character indicated, 65 a spindle, a signal carried thereby, two magnets, a flexible driving member about said spindle and having its opposite ends connected to the armatures of said respective magnets, whereby said spindle can be oppositely 70 oscillated by said respective magnets, a movable locking member adapted to engage said spindle, means tending to throw said locking member into locking position, a third magnet whose armature is so connected to said 75 locking member that when said third magnet is energized said locking member is moved from locking position, and connection between said third magnet and said two first-mentioned magnets whereby said third mag- 80 net is energized whenever either of said other magnets is energized; substantially as described.

In testimony whereof I hereunto affix my signature, in the presence of two witnesses, 85 this 27th day of August, 1902.

JAMES E. ALLISON.
